UNITED STATES PATENT OFFICE.

EUGENE J. RAY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PULLING-OVER MACHINE.

1,356,887.

Specification of Letters Patent. Patented Oct. 26, 1920.

Application filed May 3, 1917. Serial No. 166,252.

To all whom it may concern:

Be it known that I, EUGENE J. RAY, a citizen of the United States, residing at Beverly, in the county of Essex and State of Massachusetts, have invented certain improvements in Pulling-Over Machines, of which the following description, in connection with the accompanying drawings, is a specification, like reference characters on the drawings indicating like parts in the several figures.

This invention relates to machines for use in the manufacture of boots and shoes for pulling uppers over lasts, and an important object of the invention is to provide in such a machine improved upper pulling means whereby the upper may be stretched readily to the precise degree desired and may be accurately positioned upon the last before it is fastened on the last bottom.

An important feature of the invention consists in the provision in a pulling-over machine of electro-magnetic upper pulling means. Very important advantages in the use of electrical upper pulling means arise from the yielding quality of the pull effected by such means and the adaptability to precise and accurate control, whereby the strength of the pull may be readily adjusted in accordance with the observed condition of the upper stock and the pulling of the upper may be terminated without any residual tendency to stretch it further. In the construction shown each of the opposite side grippers of the machine has a solenoid associated therewith for imparting an upper pulling movement to the gripper, together with means for controlling the flow of the electrical current to permit the strength of the pull on each side of the shoe to be determined at will by the operator and the electrical circuit to be broken at any time as desired. Such a construction, particularly as adapted for effecting gripper movements in opposite directions at will, as shown, affords also opportunity for precise relative movement of the grippers for adjusting the upper on the last, and a further feature of the invention resides in the provision of electrical means for effecting relative gripper movements for adjusting the upper.

The provision of electrical upper pulling means is of particular advantage for sub-

jecting the upper to final tension, when too much force or too sudden a pull might cause the upper to tear; and in accordance with a further feature of the invention electrical upper pulling means is combined with means for initially pulling the upper over the last. The upper may thus be subjected to a final gradual yielding pull of such strength as is warranted by the condition of the stock to cause the upper to be fully stretched in such manner as to insure permanence of shape in the completed shoe without danger of tearing the stock, the electrical means permitting the pulling operation to be terminated instantly when desired, notwithstanding the yielding character of the pull effected by such means.

Still another feature of the invention resides in novel gripper controlling means, the illustrative machine having automatically operative means for locking an upper pulling gripper against movement in a direction to relax the tension of the upper and for holding it locked during the over-drawing operation. In the construction shown a fluid stop device is provided, with connections to cause the gripper to be held in the required position, together with means of control to permit return movement of the gripper.

The above and other features of the invention, including certain details of construction and combinations of parts, will now be more particularly described with reference to the accompanying drawings and pointed out in the claims.

In the drawings,

Figure 1 is a view in side elevation of portions of a pulling-over machine in which the invention is embodied,

Fig. 2 is a view in rear elevation of the side gripper operating means showing the parts as positioned at the end of the up-draw movement, portions being shown in section to illustrate the interior construction,

Fig. 3 shows in elevation a portion of the machine as viewed from the opposite side with reference to Fig. 1, this figure illustrating a later stage of the cycle of operations than that illustrated by Fig. 2, and

Fig. 4 shows more clearly than the other figures a detail of the controlling means.

The invention is illustrated in its application to a machine of a well known type,

characteristic features of which are shown and described in detail in United States Letters Patent No. 1,029,387, granted on June 11, 1912 upon an application of R. F. 5 McFeely, and only such features of the general organization of the machine as it is necessary to refer to for an understanding of the present invention will be described herein in detail. The machine includes, in 10 addition to the usual toe gripper and its operating means, side grippers 2 for engaging and pulling the forepart of a shoe upper at opposite sides of a last, these grippers being connected to updraw levers 4 15 which are pivoted at 6 to the frame of the machine and are operated by means of a path cam 8 on a cam shaft 10. The connections between the cam 8 and the updraw levers 4 comprise a slide 12 having a roll 20 14 which engages in a groove in the face of the cam, rods 16 projecting upwardly from the slide through blocks 18 in which the rear ends of the levers 4 are swiveled, and springs 20 on the rods 16, each bearing 25 at its upper end on a nut on the respective rod and at its lower end on the corresponding block 18. The side grippers 2 are thus subjected to a yielding pull the strength of which depends upon the degree 30 of compression of the springs 20 effected by the downward movement of the slide 12. It will be understood that the operative downward movement of the slide is effected by a partial rotation of the cam 8 upon 35 the actuation of the machine clutch, and that the machine then comes to rest with the upper under tension to permit the operator to inspect the work and to make any adjustment that may be necessary for 40 straightening the tip of the shoe or for otherwise correcting any inaccuracy in the position of the upper on the last, after which, upon a further actuation of the clutch, the margin of the upper is carried 45 over the last bottom and fastened and the parts are returned to starting position. It is while the upper is under tension at the end of the first stage of the cycle of operations that the means provided by the 50 present invention will be used, in the operation of the illustrative machine, for the purpose of stretching the upper still further on one or both sides, as conditions may require, or it may be for the purpose of adjusting the upper transversely of the last or for relaxing in some degree the tension 55 of the upper.

The machine herein shown is provided with electro-magnetic means for imparting 60 movement in one direction or the other as desired to either of the side grippers, the construction comprising separate connections to each of the side gripper levers and means arranged for separate control to enable 65 the operator to cause one or the other

of the levers to be moved at will. More specifically, the machine includes solenoids for operating the respective side gripper levers and a rheostat for each solenoid, together with independent connections for controlling the flow of the current.

Mounted on the frame of the machine at the rear and to one side of each updraw lever 4 is a casting 22 shaped to provide a cylindrical casing 24 within which are mounted two solenoid coils 26 and 28, and within each pair of coils is a core 30 which is to be moved upwardly by the action of the upper coil 26 and downwardly by the action of the lower coil 28. Extending 75 downwardly from the core 30 is a rod 32 provided with rack teeth in engagement with teeth on one end of a lever 34 which is pivoted to the casting 22, the other end of the lever engaging rack teeth on a rod 85 or bar 35 which is mounted for vertical movement in bearings in the casting and is pivotally connected at its lower end to a link 36 mounted on a pin 37 extending laterally from the rear end of the corresponding updraw lever 4. It will be evident that by energizing the upper coil 26 an updraw movement, effected by the upward movement of the core 30, may be imparted to the associated side gripper 2, and 90 that by energizing the lower coil 28 the gripper may be moved in the opposite direction through the downward movement of the core.

For controlling the flow of the electrical 10 current the machine is provided with a rheostat 38 for each pair of coils 26, 28, the two rheostats being mounted respectively at opposite sides of the machine frame within convenient reach of the operator. 10. Each rheostat has terminals 40 and 42 to which the respective line wires 44 and 46 are connected. The terminal 42 is connected to a second terminal 48 from which leads a wire 50 to two terminals 52 and 54 110 on the rear of the corresponding casing 24. One end of the coil 26 is connected to the terminal 52, and one end of the coil 28 is connected to the terminal 54. A direct connection is thus afforded between both the 115 coils and the line wire 46. The other end of the coil 26 is connected to a terminal 56 from which leads a wire 58 to a terminal 60 on the rheostat, this terminal being connected to one of a plurality of contact 120 blocks 62 on one side of the rheostat, these blocks being connected in series by resistance wire 64. The lower end of the coil 28 is connected to a terminal 66 on the casing 24 from which leads a wire 68 to a terminal 70 125 on the rheostat, this terminal being connected to one of a plurality of contact blocks 72 which are connected in series by means of resistance wire 74. The line wire 44 is connected permanently to terminal contact 130

plates 76 and 78 arranged for coöperation with the respective series of contacts 62 and 72.

For controlling the flow of the current through the coils 26 and 28 each rheostat includes a hand lever 80 extending forwardly from a pivot 82, and secured to this pivot for movement with the lever 80 is an arm 84 arranged to connect the terminal 76 to one or another of the series of contacts 62 and an arm 86 arranged similarly to connect the terminal 78 to one or another of the series of contacts 72. In the neutral position of the hand lever 80, shown in the drawings, the arms 84 and 86 both rest at their outer ends upon an arc-shaped supporting plate 88. In order to maintain the lever 80 in this neutral position, the frame of the rheostat is provided with a spring plunger 90, as shown more clearly in Fig. 4, the wedge-shaped end of which engages a notch in a plate 92 fast on the pivot 82. This construction affords insurance that the handle 80 shall not be accidentally displaced to cause one or the other of the coils to be energized, while permitting the handle to be readily moved in one direction or the other when the operator so desires. It will be evident that an upward movement of the handle from the neutral position shown in the drawings will cause the arm 84 first to connect the terminal plate 76 with the lowermost block 62, thereby causing the current to flow through the upper coil 26 of the solenoid and to effect an updraw movement of the associated gripper lever 4 to which the core 30 of the solenoid is connected. If a stronger pull is desired the operator raises the handle still farther, thereby cutting out portions of the resistance 64 successively. If the handle 80 is lowered from the position shown in the drawings, the arm 86 will connect the terminal plate 78 to the lowest contact block 72 and with other blocks of the same series in succession, thereby causing the gripper to be moved in a direction to relax the tension of the upper a distance increasing in proportion to decrease in the strength of the resistance 74.

In order to cause the gripper to remain in the position to which it is moved by the action of the solenoid for tensioning the upper, the machine is provided with means for locking each core 30 against downward movement even after the corresponding hand lever 80 has been returned to its neutral position. This means comprises a receptacle 94 mounted on the casting 22, the receptacle being formed to provide at one side a fluid chamber 96 and at the other side a cylinder 98 in which is mounted a piston 100 secured to the lower end of the rod 32. Communication between the chamber 96 and the cylinder 98 is controlled by means of a valve 102 which is held to its seat at times

by a spring 104. The top of the chamber 96 is in communication with the atmosphere through an opening 106, and the upper end of the cylinder 98 above the piston 100 is likewise in communication with the atmosphere through a space around the rod 32 as shown. Below the piston the cylinder 98 is preferably filled with a non-compressible fluid such as oil, and the fluid also partially fills the chamber 96 and the passage between the chamber and the cylinder to insure that in any position of the piston the portion of the cylinder below the piston and also the communicating passage shall be filled with oil. It will be evident that with this construction an upward movement of the core 30 in the solenoid, whereby the connected gripper is caused to tension the upper of the shoe, will be accompanied by an upward movement of the piston 100 which will cause oil to be drawn past the valve 102 into the cylinder 98, and that at the end of such upward movement of the piston the valve will be immediately closed by its spring 104 and the piston and its connected parts will be held positively by the fluid against retraction.

In order to permit the gripper to be moved in a direction to relax the tension of the upper by downward movement of the core 30, the machine is provided with means controlled by movement of the hand lever 80 for opening the valve 102 to permit the fluid to flow from the cylinder 98 into the chamber 96. To this end, the plate 92 which turns with the lever 80 is shaped on its periphery to provide a cam projection 108 which is arranged to engage and raise a rod 110 at the beginning of downward movement of the hand lever in the direction to cause the current to flow through the lower coil 28. This rod is arranged to engage at its upper end an arm 112 which is secured to a rock shaft 114, the rock shaft having a second arm 116 connected by a link 118 to a lever 120 pivoted on the receptacle 94, this lever being arranged to engage the upper end of the stem 122 of the valve 102. A spring 124 acts at times to uphold the lever 120 and permit the valve to be retained on its seat by the spring 104. When the lever 80 is moved downwardly, as described, the upward movement of the rod 110 causes the lever 120 to be depressed for opening the valve, and the valve is thereby retained in open position until the lever 80 has been returned to its neutral position. The core 30 is thus rendered free to move downward to retract the connected gripper.

In order to permit the side grippers to be returned to their starting position after their operation upon a shoe, the machine is provided also with automatic means for opening the valves 102 during the final stage of the cycle of operations. Conven-

iently this object is effected by utilizing the movement of a cam slide 126 with which machines of the illustrative type are provided for the purpose of imparting movement to the tack pot, this slide having an upward movement in the first or upper pulling stage of the cycle and a downward movement in the final stage of the cycle of operations of the machine. Attached to the slide 126 is a member 128 which extends rearwardly at opposite sides for engagement with blocks 130 adjustably secured on vertically sliding rods 132, the lower end of each rod 132 bearing upon an arm 134 secured to the associated rock shaft 114 on the same side of the shaft as the arm 116 previously described. By the downward movement of the slide 126 the lever 120 over each valve stem 122 will thus be depressed through the movement of the rock shafts 114 and the links 118 to open the valves 102 and afford a free passage for the fluid between the chambers 96 and the cylinders 98 during the return of the grippers to starting position. In Fig. 3 of the drawings the parts are shown in the positions which they assume while the member 128 is depressing the blocks 130 to cause the opening of the valves.

In the operation of the machine, the shoe is presented to the side and toe grippers in the usual manner and the clutch is actuated to cause the grippers to seize the upper and pull it over the last, the machine then coming to rest with the upper under tension. The position of the parts at the end of the updraw movement is illustrated in Fig. 2. The updraw movement of the grippers is effected, as previously explained, through downward movement of the slide 12 and the consequent compression of the springs 20 upon the rear ends of the levers 4, the slide being separated from the rear ends of the levers during this movement a distance in proportion to the amount of compression of the springs 20. Such movement of the levers 4 is accompanied by an upward movement of the cores 30 in the solenoids by reason of the connections between the levers and the cores, the pistons 100 also moving upwardly and drawing a portion of the fluid from the chambers 96 past the valves 102 into the cylinders 98. The cores 30 stand initially below a central position with reference to the respective pairs of coils 26 and 28 to cause the cores to assume a substantially central position as illustrated in Fig. 2 in the first updraw movement of the grippers.

While the machine is at rest with the upper under tension the operator is afforded an opportunity to inspect the work and to determine whether any change in the position of the upper upon the last is required in order to produce a symmetrical

shoe or whether the upper may be advantageously pulled to a greater extent on one or both sides or whether the tension should be relaxed in any degree at one side or the other. If it is desired to adjust the upper transversely of the last, one of the levers 80 may be lowered to cause the lower coil 28 on that side of the machine to be energized for effecting a movement of the corresponding side gripper in a direction to relax the tension of the upper on that side to a greater or less degree, and simultaneously the handle on the other side of the machine may be raised to cause the other side gripper to pull the upper transversely of the last through the action of the other solenoid. By manipulating the levers 80 the operator may thus secure the precise adjustment of the upper transversely of the last which is required. In case it appears to be advantageous to impart additional tension to the upper, one or both levers 80 may be raised to render one or both of the coils 26 effective for imparting a further updraw movement to the side grippers. If it is desired to relax the tension of the upper in any degree, one or both of the levers 80 will be lowered, this movement serving also to open the corresponding valve or valves 102 in the manner previously explained. As soon as the upper has been adjusted or tensioned in the manner required, the lever or levers 80 are returned to neutral position and the side grippers are retained, through the action of the fluid upon the pistons 100, in the positions to which they have been moved.

After the upper has been adjusted and tensioned as required, the machine is started the second time in the usual manner to cause the margin of the upper to be carried over the sole or innersole on the last bottom and fastened in place, after which the parts of the machine return to their starting positions. It will be evident that during such overdraw movement of the grippers to carry the margin of the upper over the sole or innersole the fluid locking devices hold the grippers against movement toward the plane of the shoe bottom and thus insure that the margin of the upper shall be drawn tightly into position to be fastened. During the latter part of this stage of the cycle of operations the valves 102 are opened in the manner described to permit the return movement of the grippers effected by the action of the slide 12.

It will be readily understood from a consideration of the well-known characteristic movements of the tack pot operating slide 126 in machines of the general type illustrated, effected in the single revolution of the cam shaft 10, that the valves 102, after they have been opened as above described, are held open until the slide 126 is moved

upwardly in the first stage of the cycle of operations of the machine upon another shoe. The valves are thus released to the action of their closing springs by the automatic action of their controlling means in the upper pulling stage of the cycle to render them effective to lock the side grippers against retractive movement from the position which they assume in their first 10 updraw movement as well as from any position to which they may be moved subsequently by the action of the electrical means.

Although the invention is herein shown as embodied in means for operating and controlling the side grippers of a pulling-over machine, it will be understood that in many of its aspects the invention is not limited in respect to the location of the gripper or 15 grippers. It will also be evident that the gripper locking means, although shown herein in combination with electrical gripper operating means, presents features of utility not necessarily dependent upon operating means of this particular character, and that in many of its aspects also the invention is not limited to locking means of the particular type illustrated.

Having described the invention, what I 20 claim as new and desire to secure by Letters Patent of the United States is:

1. A pulling-over machine having, in combination, a gripper for engaging the margin of an upper on a last, means for operating 25 said gripper to pull the upper, and electro-magnetic means for operating the gripper subsequently to increase the tension of the upper.

2. A pulling-over machine having, in combination, a gripper for engaging the margin of an upper on a last, a power shaft, connections between said gripper and power shaft for imparting an upper pulling movement to the gripper, and electro-magnetic 45 means connected to the gripper for operating the gripper independently of said power shaft.

3. A pulling-over machine having, in combination, means for pulling an upper over 50 a last and holding it under tension, and electro-magnetic means arranged to be operated while the upper is held under tension for increasing the tension of the upper.

4. A pulling-over machine, having in combination, grippers for engaging an upper at opposite sides of a last, means for operating said grippers to pull the upper transversely over the last, and electro-magnetic means for imparting a further tensioning 60 movement to said grippers.

5. A pulling-over machine having, in combination, grippers for engaging an upper at opposite sides of a last, power operated means having a definite range of movement for operating said grippers to pull the 65

upper, and electro-magnetic means connected to the grippers to enable the operator to cause the tension of the upper to be increased by further movement of the grippers.

70

6. A pulling-over machine having, in combination, a gripper for engaging the margin of an upper on a last, means for operating said gripper to pull the upper and then to hold the upper under tension, and electro-magnetic means connected to the gripper for moving the gripper in either direction while the upper is under tension for increasing or decreasing respectively the tension of the upper.

80

7. A pulling-over machine having, in combination, a gripper for engaging the margin of an upper on a last, an updraw lever connected to said gripper, a power shaft, yielding connections between said lever and power shaft for imparting an upper pulling movement to the gripper, and electro-magnetic means connected to said lever for effecting a movement of the gripper independently of the power shaft while the upper 90 is under tension.

85

8. A pulling-over machine having, in combination, a gripper for engaging an upper on a last, means for operating said gripper to pull the upper, and electro-magnetic 95 means comprising a solenoid and connections to the gripper for imparting a further upper tensioning movement to the gripper.

9. A pulling-over machine having, in combination, a gripper for engaging an upper on a last, means for operating said gripper to pull the upper, and supplemental gripper operating means comprising a solenoid and a core in the solenoid connected to the 100 gripper.

105

10. A pulling-over machine having, in combination, a gripper for engaging an upper on a last, an updraw lever connected to said gripper, a power shaft, connections between the power shaft and said lever including a spring through which movement is imparted to the gripper, a solenoid, a core in the solenoid connected to said lever, and means for controlling the flow of electrical current in the solenoid to cause the gripper 115 to be operated independently of the power shaft.

11. A pulling-over machine having, in combination, grippers for engaging an upper and pulling it over a last, and electro-magnetic means for enabling the operator to effect a relative movement of said grippers for adjusting the upper on the last.

120

12. A pulling-over machine having, in combination, grippers for engaging an upper at opposite sides of a last, and electro-magnetic means connected to said grippers for enabling the operator to effect an adjusting movement of the upper transversely of the last.

125

65 130

13. A pulling-over machine having, in combination, grippers for engaging an upper at opposite sides of a last, means for operating said grippers to pull the upper, supplemental electro-magnetic operating means connected to each side gripper, and mechanism for controlling the operation of said electro-magnetic means to enable the operator to cause an additional movement of one or both of the side grippers.

14. A pulling-over machine having, in combination, grippers for engaging an upper at opposite sides of a last, means for operating said grippers to cause them to pull the upper and then to hold the upper under tension, and electro-magnetic means constructed and arranged for separate control in respect to each side gripper for effecting at the will of the operator a subsequent movement of one or both of said grippers either in a direction to increase the tension of the upper or in a direction to decrease said tension.

15. A pulling-over machine having, in combination, a gripper for engaging an upper on a last, and means for effecting relative movement of said gripper and the last to pull the upper and for then stopping the upper pulling operation without any residual tendency in said means to continue such relative movement, said means comprising electro-magnetic mechanism and a device for making and breaking the electrical circuit in said mechanism.

16. A pulling-over machine having, in combination, a gripper for engaging an upper on a last, and means for operating said gripper to pull the upper and for then stopping the upper pulling operation without any residual tendency in the operating means to continue the movement of the gripper, said operating means comprising a solenoid connected to the gripper, and means for making and breaking the electrical circuit in said solenoid.

17. A pulling-over machine having, in combination, a gripper for engaging an upper on a last, electro-magnetic means for operating said gripper, and controlling means to enable the operator to break the electrical circuit at any time during the upper pulling operation to terminate the application of force to the gripper.

18. A pulling-over machine having, in combination, a gripper for engaging an upper on a last, a solenoid, connections between the solenoid and said gripper, and means for controlling the flow of electrical current through said solenoid to cause the gripper to be moved in different directions at the will of the operator.

19. A pulling-over machine having, in combination, grippers for engaging an upper on a last, a solenoid associated with each gripper, a core in each solenoid connected to

the respective gripper for imparting an upper pulling movement to the gripper, and a separately controlled rheostat for each solenoid for controlling the flow of current through the solenoid to vary the degree of tension of the upper.

20. A pulling-over machine having, in combination, a gripper for engaging an upper on a last, a solenoid comprising separate coils, a core arranged to be moved in opposite directions by the action of the respective coils, a connection between said core and the gripper for imparting movement to the gripper, and means for controlling the flow of electrical current through said coils.

21. A pulling-over machine having, in combination, a gripper for engaging an upper on a last, means for operating said gripper to pull the upper and then to hold the upper under tension, a solenoid comprising separate coils, a core arranged to be moved in opposite directions by the respective coils, a connection between said core and the gripper for imparting movement to the gripper, and means for controlling the flow of electrical current through said coils to cause the gripper either to increase or to relax the tension of the upper.

22. A pulling-over machine having, in combination, an upper engaging gripper, means for operating said gripper to pull an upper over a last, a solenoid comprising two coils arranged end to end, a core within said coils, means connecting said core to the gripper arranged to cause the core to be moved to a substantially intermediate position with reference to said coils by said pulling movement of the gripper, and means for directing electrical current through one or the other of said coils for effecting a supplemental movement of the gripper to increase or relax the tension of the upper.

23. A pulling-over machine having, in combination, an upper engaging gripper, operating means for imparting movement to said gripper to pull an upper over a last, and fluid means for locking said gripper against movement in a direction to relax the tension of the upper.

24. A pulling-over machine having, in combination, an upper engaging gripper, means for imparting movement to said gripper to pull an upper over a last, a cylinder, a piston in said cylinder, the cylinder having a fluid passage communicating therewith, means connected to said gripper for effecting a relative movement of the cylinder and piston during the updraw movement of the gripper, and a valve for said passage arranged to open to permit said relative movement of the cylinder and piston and to close to lock the gripper against return movement.

25. A pulling-over machine having, in combination, an upper engaging gripper,

means for imparting movement to said gripper to pull an upper over a last, a receptacle for liquid, a cylinder, means providing a passage between said receptacle and cylinder, a piston in the cylinder, means connecting the piston to said gripper for moving the piston during the updraw movement of the gripper, and a check valve for said passage arranged to permit a flow of liquid in the passage during said movement of the gripper and to prevent a return flow.

26. A pulling-over machine having, in combination, an upper engaging gripper, means for imparting movement to said gripper to pull an upper over a last, a cylinder, a piston in said cylinder, means connected to said gripper for effecting a relative movement of the cylinder and piston for drawing fluid into the cylinder during the updraw movement of the gripper, and a valve for preventing return of the fluid from the cylinder.

27. A pulling-over machine having, in combination, an upper engaging gripper, means for imparting movement to said gripper to pull an upper over a last, a receptacle for liquid, a cylinder, means of communication between said receptacle and cylinder, a piston in the cylinder, means connecting the piston to the gripper to cause the piston to draw liquid into the cylinder during the updraw movement of the gripper, and means for locking the gripper against retraction from its upper tensioning position by preventing return of the fluid.

28. A pulling-over machine having, in combination, an upper engaging gripper, means for imparting upper pulling movement to said gripper, fluid means for automatically locking the gripper against movement in a direction to relax the tension of the upper, and means for unlocking the gripper.

29. A pulling-over machine having, in combination, an upper engaging gripper, means for imparting movement to said gripper to pull an upper over a last, a cylinder having a fluid passage communicating therewith, a piston in the cylinder, means connected to said gripper for effecting a relative movement of the cylinder and piston to cause a flow of fluid in said passage during the updraw movement of the gripper, a valve for preventing return of the fluid to cause the gripper to be locked against retraction from its upper tensioning position, and means enabling the operator to open said valve.

30. A pulling-over machine having, in combination, an upper engaging gripper, means for imparting movement to said gripper to pull an upper over a last, a cylinder having a fluid passage communicating therewith, a piston in the cylinder, means connected to said gripper for effecting a rel-

ative movement of the cylinder and piston to cause a flow of fluid in said passage during the updraw movement of the gripper, a valve for preventing return of the fluid to cause the gripper to be locked against retraction from its upper tensioning position, and automatic means for opening said valve to permit the gripper to be returned to starting position.

31. A pulling-over machine having, in combination, an upper engaging gripper, electro-magnetic means for operating said gripper to pull an upper over a last, and means for locking the gripper against retraction from its upper tensioning position.

32. A pulling-over machine having, in combination, an upper engaging gripper, electro-magnetic means for moving said gripper either in a direction to pull an upper over a last or in direction to relax the tension of the upper, a rheostat for controlling the operation of said means, means for locking the gripper against retraction from its upper tensioning position, and means controlled by said rheostat for unlocking the gripper to permit its movement in the direction to relax the tension.

33. A pulling-over machine having, in combination, an upper engaging gripper, electro-magnetic means for operating said gripper, a member for controlling the flow of electrical current in said means, means for locking the gripper against movement in one direction, and means operated by said controlling member for unlocking the gripper.

34. A pulling-over machine having, in combination, an upper engaging gripper, electro-magnetic means for operating said gripper, a member for controlling the flow of electrical current in said means, fluid means including a valve for locking the gripper against movement in one direction, and means operated by said controlling member for opening said valve.

35. A pulling-over machine having, in combination, an upper engaging gripper, electro-magnetic means for moving said gripper either in a direction to pull an upper over a last or in a direction to relax the tension of the upper, mechanism for controlling the flow of electrical current in said means, fluid means including a valve for locking the gripper against retraction from upper tensioning position, and means operated by said controlling mechanism for opening said valve when the gripper is to be moved in the direction to relax the tension.

36. A pulling-over machine having, in combination, an upper engaging gripper, a solenoid, a core in said solenoid connected to the gripper for imparting upper tensioning movement to the gripper, and fluid means connected to said core for locking the

gripper against retraction from upper tensioning position.

37. A pulling-over machine having, in combination, an upper engaging gripper, a solenoid, a core in said solenoid connected to the gripper for imparting upper tensioning movement to the gripper, means for controlling the flow of electrical current in said solenoid, fluid means including a valve 10 for locking the gripper against retraction from upper tensioning position, and mechanism operated by said controlling means for opening said valve.

38. A pulling-over machine having, in combination, an upper engaging gripper, means for operating said gripper to pull an upper over a last, supplemental means for operating said gripper to increase the tension of the upper, and fluid means for locking the gripper against retraction from its position of increased tension.

39. A pulling-over machine having, in combination, an upper engaging gripper, means for operating said gripper to pull an upper over a last, supplemental means for operating said gripper to increase the tension of the upper, fluid means including a valve for locking the gripper against retraction from its position of increased tension, and means for opening said valve to permit the gripper to return to starting position.

40. A pulling-over machine having, in combination, an upper engaging gripper, means for operating said gripper to pull an upper over a last, electro-magnetic means for imparting a supplemental pulling movement to said gripper for further tensioning the upper, and means for locking the gripper against retraction from its position of increased tension.

41. A pulling-over machine having, in combination, a gripper for engaging an upper on a last, power-driven means having a prescribed range of action for effecting relative movement of the gripper and the last to pull the upper, and electro-magnetic means connected to said gripper and arranged for use under manual control subsequent to said upper pulling operation for imparting movement to the gripper in a direction to change the tension under which the upper is held by the gripper.

42. A pulling-over machine having, in combination, a gripper for engaging an upper on a last, means for effecting relative movement of said gripper and the last to pull the upper and for then holding the upper under tension, and electro-magnetic means for effecting relative movement of the last and said gripper while the upper is thus held under tension to change the tension under which the upper is held.

43. A pulling-over machine having, in combination, grippers for engaging an up-

per on a last, means for effecting relative movement of the last and said grippers to pull the upper, and independently controlled electro-magnetic operating mechanisms connected respectively to different 70 grippers for moving one or more of the grippers in different directions at the will of the operator to change the tension under which the upper is held or to adjust the upper on the last.

75 44. A pulling-over machine having, in combination, grippers for engaging an upper on a last, and independently controlled electro-magnetic operating mechanisms connected respectively to different grippers for 80 imparting movement to one or more of said grippers at the will of the operator.

45. A pulling-over machine having, in combination, a gripper for engaging an upper on a last, electro-magnetic operating 85 means, and controlling mechanism for causing said operating means to effect relative movement of the gripper and the last either to pull the upper or to relax the tension of the upper.

90 46. A pulling-over machine having, in combination, a gripper for engaging an upper on a last, electro-magnetic gripper operating means, and controlling means for rendering said operating means effective to 95 move the gripper either in a direction to pull the upper or in a direction to relax the tension of the upper.

100 47. A pulling-over machine having, in combination, grippers for engaging an upper at opposite sides of a last, means for effecting relative movement of said grippers and the last to pull the upper, independently controlled electro-magnetic operating mechanisms connected respectively 105 to said opposite side grippers for moving either gripper at the will of the operator in a direction to increase the tension of the upper, and a fluid lock for holding either gripper against movement toward the plane 110 of the shoe bottom while the other gripper is operated by its electro-magnetic mechanism.

115 48. A pulling-over machine having, in combination, a gripper for engaging an upper on a last, means for operating said gripper to pull the upper, a fluid lock including a fluid retaining valve for holding said gripper against retractive movement, means for opening said valve at a definite time in 120 the cycle of operations of the machine to unlock the gripper, and additional manually operative means for enabling the operator to open said valve at will.

125 49. A pulling-over machine having, in combination, a gripper for engaging an upper on a last, means for effecting relative movement of the last and said gripper to pull the upper, means for operating the gripper to draw the margin of the upper 130

inward over the bottom of the last, and a fluid lock for holding said gripper against movement toward the plane of the shoe bottom to render it effective to tighten the upper in its overdrawing movement.

5. 50. A pulling-over machine having, in combination, a gripper for engaging an upper on a last, means for operating said gripper to pull the upper, additional means for 10 moving the gripper yieldingly to increase the tension of the upper, and means for locking the gripper against retraction from its position of increased tension.

15. 51. A pulling-over machine having, in combination, an upper engaging gripper, means having a prescribed range of movement for operating said gripper to pull the upper, additional means for imparting at the will of the operator a supplemental pulling movement of variable extent to said gripper, and means automatically operative to lock the gripper against retractive movement from any position to which it is moved by either of said different means.

20. 52. A pulling-over machine having, in combination, an upper engaging gripper, a solenoid, means for operating said gripper to pull the upper yieldingly, electro-magnetic means comprising a solenoid for operating said gripper to impart a supplemental yielding pull to the upper, and means for locking the gripper against retractive movement when the current in said solenoid is broken.

25. 53. A pulling-over machine having, in combination, upper gripping means, electro-magnetic means for operating said gripping means to pull the upper, controlling means to enable the operator to break the electrical circuit at will and thus to relieve the gripping means from the force of said operating means, and means automatically operative to hold the gripping means against retractive movement in response to the pull 40 of the upper when the circuit is thus broken.

50. 54. A pulling-over machine having, in combination, a plurality of grippers for engaging an upper on a last, electro-magnetic gripper operating means comprising a plurality of solenoids connected respectively to the different grippers, and means for controlling the flow of electrical current in the different solenoids to cause one or more of the grippers selectively to pull the upper at 55 the will of the operator.

55. 55. A pulling-over machine having, in combination, an upper engaging gripper, means for imparting operative movement to said gripper, a member connected to said gripper to be moved idly during said operative movement of the gripper, and electro-magnetic means for imparting a subsequent movement to the gripper through said member.

60. 56. A pulling-over machine having, in

combination, an upper engaging gripper, means for imparting operative movement to said gripper, a member connected to said gripper to be moved idly during said operative movement of the gripper, a solenoid in 70 operative relation to said member, and means for causing said solenoid to be energized to impart a supplemental movement to the gripper.

57. 57. A pulling-over machine having, in combination, an upper engaging gripper, a gripper operating lever unyieldingly connected to said gripper, a solenoid connected to said lever for operating the lever, and means for controlling the flow of electrical 80 current in said solenoid to initiate or to stop the pulling of the upper.

58. 58. A pulling-over machine having, in combination, an upper engaging gripper, a gripper operating lever, a solenoid connected to said lever, means for controlling the flow of electrical current in said solenoid, and means also connected to said lever for locking the gripper against retractive movement when the electrical circuit is broken. 90

59. 59. A pulling-over machine having, in combination, an upper engaging gripper, a lengthwise movable bar arranged to be operated by said solenoid and connected to the gripper, and means connected to said bar 95 for locking the gripper against retractive movement.

60. 60. A pulling-over machine having, in combination, an upper engaging gripper, a lengthwise movable bar, a solenoid at one 100 end of the bar for operating it, automatically operative locking means at the other end of the bar, and connections between said bar and the gripper for imparting movement to the gripper. 105

61. 61. In a machine of the class described, the combination with an upper engaging gripper, of means for imparting an upper pulling movement to said gripper, means for locking the gripper against retractive movement, and means arranged to receive operative movement in said upper pulling movement of the gripper for rendering said locking means effective to hold the gripper. 110

62. 62. In a machine of the class described, the combination with an upper engaging gripper, of means for imparting an upper pulling movement to said gripper, means for moving the gripper subsequently in a direction to increase the tension of the upper, means for locking the gripper against retractive movement, and means operative in said first movement of the gripper for rendering said locking means effective to hold the gripper. 120

63. 63. In a machine of the class described, the combination with an upper engaging gripper, of means for imparting an upper pulling movement to said gripper, means for subsequently imparting an additional 125

movement to the gripper, means for locking the gripper against retraction from the position attained in said additional movement, and means automatically operative 5 during the cycle of operations of the machine for rendering said locking means alternately effective and ineffective to hold the gripper.

64. In a machine of the class described, 10 the combination with an upper engaging gripper, of means for operating said gripper, a bar movable with the gripper, means coöperating with said bar to lock the gripper against retractive movement, and means 15 for controlling said locking means to render it either effective or ineffective to hold the gripper.

65. In a machine of the class described, 20 the combination with an upper engaging gripper, of mechanism for operating said gripper first to pull the upper and then to overdraw the upper, power operated means under control of the operator for imparting a supplemental movement to the gripper 25 after its pulling movement and prior to the overdraw, and means for locking the gripper against retractive movement from the position assumed in said supplemental movement and for holding it locked throughout 30 the overdrawing operation.

66. In a machine of the class described, 35 the combination with an upper engaging gripper, of power operating means, connections to the gripper through which it may be moved by said operating means either to pull the upper or to relax the tension, controlling means normally positioned to render the operating means inoperative to move the gripper and movable in opposite 40 directions to cause the gripper to be moved in the different directions alternatively, means operative in said normal position of the controlling means for locking the gripper against movement in one direction, and 45 means arranged to be operated by the controlling means to cause said locking means to release the gripper when the gripper is to be moved in said direction.

67. In a machine of the class described, 50 the combination with means for gripping an upper on a last, of mechanism for effecting relative movement of said gripping means and the last to pull the upper yieldingly, means for operating the gripping means subsequently to overdraw the upper, and means 55 for subjecting said gripping means to positive control in respect to its relation to the plane of the shoe bottom throughout its overdrawing movement.

68. In a machine of the class described, 60 the combination with an upper engaging gripper, of means for operating said gripper to pull the upper comprising an operating

member and connections constructed and arranged to permit relative yielding movement 65 between the gripper and said member, means for moving the gripper to draw the margin of the upper inward over the bottom of the last, and means for preventing such relative yielding movement in the gripper operating connections throughout the overdrawing movement of the gripper.

69. In a machine of the class described, 70 the combination with means for gripping an upper on a last, of mechanism for effecting relative movement of said gripping means and the last to pull the upper yieldingly, means for operating the gripping means subsequently to overdraw the upper, and means 75 for locking the gripping means and holding it against yield in a direction toward the plane of the shoe bottom throughout the overdrawing operation.

70. In a machine of the class described, 80 the combination with an upper engaging gripper, of means for imparting an upper pulling movement to said gripper, means for locking the gripper against retractive movement from the position attained in said upper pulling movement, and means automatically operative during the cycle of operations of the machine for rendering said locking means alternately effective and ineffective to hold the gripper.

71. In a machine of the class described, 85 the combination with upper gripping means, of mechanism for operating said gripping means first to pull the upper and then to overdraw the upper, means for locking said gripping means against yielding movement 90 in a direction toward the plane of the shoe bottom during the overdrawing operation, and mechanism for rendering said locking means effective to hold the gripping means and for operating it to unlock the gripping 95 means only after the overdrawing operation has been completed.

72. In a machine of the class described 100 having a cycle of operations wherein the upper is pulled and then held under tension with the machine at rest and is overdrawn when the machine is again started, the combination with upper gripping means and mechanism for operating it to pull and to overdraw the upper, of means for locking 105 said gripping means against yielding movement in a direction toward the plane of the shoe bottom during the overdrawing operation, and mechanism arranged to be operated in that stage of the cycle of operations in 110 which the pulling of the upper is effected for rendering said locking means effective to hold the gripping means.

In testimony whereof I have signed my name to this specification.

EUGENE J. RAY.

It is hereby certified that in Letters Patent No. 1,356,887, granted October 26, 1920, upon the application of Eugene J. Ray, of Beverly, Massachusetts, for an improvement in "Pulling-Over Machines," errors appear in the printed specification requiring correction as follows: Page 9, lines 26-27, claim 52, strike out the words and comma "a solenoid,"; same page, line 92, claim 59, after the word "gripper" insert the words and comma *a solenoid*; and that the said Letters Patent should be read with these corrections therein that the same may conform to the record of the case in the Patent Office.

Signed and sealed this 1st day of March, A. D., 1921.

[SEAL.]

L. B. MANN,

Acting Commissioner of Patents.

Cl. 12—4.
